NOSEPIECE FOR MICROSCOPES

George S. MacDenald, Buffalo, N. Y., assignor to
Spencer Lens Company, Buffalo, N. Y.

Application February 18, 1935, Serial No. 7,039

4 Claims. (Cl. 38—39)

This invention relates to improvements in nose pieces for microscopes.

The objects of this invention are to provide an improved nose piece in which the rotary part is pivoted to a stationary portion of the microscope by means of an improved pivotal mounting which affords a more secure and accurate support for the rotary part, so that the objectives carried by the nose piece may be more accurately aligned and supported with reference to the optical axis of the instrument; also to provide a bearing of this kind in which a pair of frusto-conical or tapering members bear against corresponding faces of the rotatable part of the nose piece, and in which one of the wedge-shaped members is adjustable toward the other for insuring an accurate and rigid support of the pivoted part of the nose piece; also to improve the construction of nose pieces for microscopes in other respects hereinafter specified.

In the accompanying drawing:

Fig. 1 is an elevation, partly in section, of the lower end of the body tube of a microscope and having a nose piece embodying this invention applied thereto.

Fig. 2 is a fragmentary sectional view, partly in elevation, of the nose piece, the section being taken approximately on line 2—2, Fig. 1.

Fig. 3 is a similar sectional view in which the pivot of the nose piece is also shown in section.

Fig. 4 is a transverse sectional view thereof on line 4—4, Fig. 3.

Fig. 5 is a sectional perspective view of the movable wedge or bearing member of the pivotal support.

In Fig. 1, A represents the lower portion of a body tube of a microscope, to the lower end of which a nose piece embodying this invention is applied. The nose piece includes a fixed or stationary part 7 which may be suitably secured to any fixed part of the microscope. In the construction illustrated, this nose piece is secured to the lower end of the body tube A and for this purpose a sleeve 8 having an outwardly extending flange 9 on the lower end thereof is secured through an aperture or sleeve 10 in the fixed part 7 of the nose piece. The upper portion of the sleeve 8 may be suitably secured within the body tube in any suitable manner, for example, such as a threaded engagement with a part of the body tube and the flange 9 bears against a shoulder formed in the aperture 10 of the fixed part of the nose piece. It will be understood, however, that the fixed part of the nose piece may be secured in any other manner, either to the

body tube or another fixed part of the microscope.

The fixed part 7 of the nose piece serves as a support on which a rotatable part 12 of the nose piece may be mounted and this rotatable part has a number of objectives B secured thereto in such a manner that by turning the movable part of the nose piece about its axis of rotation, the optical axes of the several objectives mounted thereon may one at a time be placed into alignment with the optical axis of the body tube. In the particular construction shown, the stationary and rotatable parts 7 and 12 are in the form of disks, the part 12 having a flange 14 cooperating in the usual manner with the fixed part 7 to form a substantially dust proof enclosure for the upper ends of the objectives. Nose pieces as thus far described have heretofore been used in connection with microscopes and of themselves do not constitute a part of this invention.

It will be realized that in order to provide for a high degree of accuracy in alining the optical axis of any one of the objectives carried by the nose piece correctly with reference to the optical axis of the microscope, it is necessary to provide an accurate pivotal mounting of the rotatable part 12 of the nose piece with reference to a fixed part of the microscope, and in the construction shown for this purpose, an improved pivotal bearing is provided for this purpose and comprises a pin or post 15 which is rigidly secured to the stationary or fixed part 7 of the nose piece and this post or pin is preferably provided adjacent to the part 7 with a tapering or substantially frusto-conical bearing portion 16 which may, if desired, be formed integrally with the post 15 as shown in Fig. 3. The post has a portion which extends beyond the frusto-conical part 16 and is provided near the outer portion thereof with a movable tapering frusto-conical bearing member 17. Preferably, this bearing member 17 is held against turning with reference to the post 15 and for that purpose, the post is provided at its end portion with a flattened side or face 18, which is adapted to engage with a correspondingly flattened portion 19 in a central aperture 20 of the bearing member 17. This arrangement permits the bearing member 17 to move lengthwise of the post without turning relatively to the same. It will be obvious that any other means for permitting lengthwise movement of this bearing member relatively to the post without turning may be employed in place of that shown.

The movable bearing member 17 may be held on the post 15 and urged lengthwise thereof by

any suitable means, a set screw 22 engaging in a threaded aperture in the end of the post being shown for this purpose, the head of the set screw extending into engagement with the outer face 5 of the bearing member 17 and by tightening the set screw, the bearing member 17 may be moved toward the other bearing member 16.

The rotatable part 12 of the nose piece is provided with a tapering or frusto-conical bearing surface 25 arranged to cooperate with the correspondingly tapered bearing portion 16 of the pivot post 15 and in order to provide an accurate mounting for the rotatable part of the nose piece, a hub portion or extension 26 is preferably formed 15 in this part 12 which preferably extends at a distance from the tapered or frusto-conical surface 25 and is provided near its outer end with a tapered or frusto-conical bearing surface 27 adapted to cooperate with the bearing member 20 17. The portion of the rotatable member 12 between its two bearing surfaces 25 and 27 is preferably spaced from the cylindrical portion 25 of the post 15 so that the pivot bearing is formed only at the frusto-conical or tapering bearing 30 faces. It will be obvious that by tightening the set screw 22, the bearing member 17 may be moved toward the other bearing member 16, thus insuring a correct centering of the rotatable part 12 of the nose piece at all times, even after considerable wear of the contacting faces of the bearing parts has taken place. The set screw 35 22 may also be adjusted as may be desired to obtain the desired friction between the frusto-conical faces to yieldingly hold the rotatable part of the nose piece in any position into which it is set.

The construction described makes it possible to provide for the rotatable part of the nose piece an extended bearing surface by providing on 40 the movable part of the nose piece an outwardly extending hub or projection 26 which permits the spacing apart of the two frusto-conical bearing surfaces to such an extent as to provide a very secure and firm mounting for the rotatable part 45 of the nose piece, so that the objectives may be held in correct relation to the optical axis of the microscope.

I claim as my invention:

1. A nose piece for a microscope including a 50 fixed part and a rotatable part carrying a plurality of objectives, any one of which may be placed into an operative position by rotation of said rotatable part, said fixed part having a pivot post rigidly secured thereto about which said rotatable part may turn, said rotatable part having oppositely disposed faces arranged in sub-

stantially frusto-conical relation to said post and said pivot post having substantially frusto-conical portions cooperating with said faces, one of said portions being movable toward and from the other, and means for pressing said portions into engagement with said faces. 5

2. A nose piece for a microscope including a fixed part and a rotatable part carrying a plurality of objectives, any one of which may be placed into an operative position by rotation of 10 said rotatable part, said fixed part having a pivot post rigidly secured thereto about which said rotatable part may turn, said rotatable part having a hub portion provided at opposite ends thereof with oppositely disposed faces tapering with 15 relation to the axis of said pivotal post, said pivot post having correspondingly tapering members adapted to be pressed into wedging engagement with said faces for pivotally supporting said rotatable part. 20

3. A nose piece for a microscope including a fixed part and a movable part having a plurality of objectives mounted thereon, and a pivotal connection between said parts which includes a post formed on one of the said parts and having bearing members supported thereon and spaced apart and tapering in opposite directions with reference to the axis of said pivotal connection, the other part having a hub portion formed thereon provided with correspondingly tapering bearing faces 30 near opposite ends thereof and arranged to cooperate with the bearing members of said post, the portion of said post between said bearing members being out of contact with said hub, to support said hub on said post adjacent to 35 the opposite ends of said hub.

4. A nose piece for a microscope including a fixed part and a movable part having a plurality of objectives mounted thereon, and a pivotal connection between said parts which includes 40 a post formed on one of the said parts and having tapering bearing members supported thereon and spaced apart, one of said bearing members being mounted adjacent to the end of said post and being held against rotation relatively to said post and movable lengthwise thereof, the other part of the nose piece having a hub formed thereon and provided at opposite ends of said hub with tapering bearing faces adapted to be engaged by the bearing faces of said post, 50 and a set screw engaging the end of said post and the adjacent bearing member for urging said bearing member toward the other bearing member to press said bearing members against said faces. 55

GEORGE S. MACDONALD.
